MATCH RECEPTACLE

Application filed March 14, 1927. Serial No. 175,212.

The present invention relates to receptacles for matches and is herein disclosed as embodied in a portable match safe which may be caused to expose and automatically ignite 5 one match at a time and thereafter to extinguish and release the same.

In carrying out the invention means are provided in a match receptacle for selecting, exposing and lighting one match at a time. 10 The match is then released and thoroughly extinguished before it is finally discarded from the receptacle.

The various features of the invention consist in the devices, combinations, and arrangement of parts hereinafter described and claimed and together with the advantages to be obtained thereby will be readily understood by one skilled in the art from the following description taken in connection with 15 the accompanying drawings, in which Fig. 1 is a view in side elevation of a match safe illustrating one form of the invention; Fig. 2 is a bottom plan view of the device looking up from below; Fig. 3 is a top plan view; 20 Fig. 4 is a left end elevation of the device; and Fig. 5 is a sectional plan view taken on the line 5—5 of Fig. 1.

The pocket match safe herein disclosed as the preferred embodiment of the invention 25 comprises an outer casing within which is mounted a magazine for the matches narrowed at one end to permit the feeding of only one match at a time. Spring pressed wires tend to force the matches towards the narrow end of the magazine from which they 30 may be ejected one at a time, by means of two plungers provided for this purpose. The plungers are ordinarily held in depressed position against the pressure of suitable 35 springs by a spring catch. When it is desired to light a match, the catch is released permitting the plungers to rise and a match is forced from the magazine into the space formerly occupied by the plungers. By 40 pressing down one of the plungers the match is partially ejected from the container forcing open the lid of the match safe and through the frictional contact of the match head with the surface of the lid causing the match to 45 be lighted. When the match is to be ex-

tinguished the second plunger is forced downward completely ejecting the match which is smothered by the lid closing under the pressure of a torsion spring as the match leaves its groove. 55

Referring more specifically to the drawings the device takes the form of an outer casing 1 within which is mounted the inner box or magazine 2 containing the matches 3. The magazine is narrowed at 2^a to form at one 60 end the narrow neck 2^b through which the matches may be fed one at a time to the ejector. At each side of the magazine between the inner and outer casings are fixedly mounted the horizontal rods or guideways 65 4 for the match feeder wires 6. These wires are slidably mounted on the rods 4 and extend across the magazine passing through appropriate slots 6^a cut in the magazine walls. Compression springs 5 coiled about the rods 70 6 between the wire feeders and the end of the casing tend to force the wire feeders towards the narrow end of the magazine and insure the proper feeding of the matches to the ejector. At the lower left hand end 75 of the casing 1 as viewed in Fig. 1 is formed the hinge support 7^a carrying a hinge pin 8 for the lid 10 of the match safe which is held normally in closed position by the torsion spring 9. 80

The means for ejecting the matches one at a time from the magazine comprise a plunger 11 for partially ejecting or exposing the match, and the plunger 12 for thereafter entirely ejecting the match from its groove. 85 The plunger 11 is in the form of a comparatively broad strip and is mounted in guideways formed by the end plate 7 adjacent the end of the narrow portion 2^b of the magazine. Tension springs 11^b secured at their lower 90 ends to hooks offset from the plunger 11 and at their upper ends to eyes formed in the casing 1 tend to raise the plunger to the dotted position shown in Fig. 1. The plunger 11 is ordinarily held in depressed position by 95 the engagement of a spring catch 13 in a corresponding notch 11^c in the plunger. The plunger 12 for completely ejecting the used match from its groove is mounted to slide in a groove formed in the end plate 7 behind the 100

plunger 11, and is provided at its upper end with a curved portion overlapping the plunger 11. With this arrangement of the parts the plunger 12 will be drawn up with the plunger 11 under the influence of the springs 11^b when the catch 13 is released preparatory to the lighting of a new match.

The operation of the device is as follows:— When the spring catch 13 is released allowing the plungers 11 and 12 to assume the positions indicated in dotted lines in Fig. 1, a match will be forced by the feeding mechanism into the groove formerly occupied by the plungers. The plunger 11 is now depressed causing the match to be forced downward against the lid 10 which is swung open against the pressure of its spring 9 by the continued movement of the match. During this operation the match head will rub along a specially prepared surface 10^c of the lid causing the match to ignite. The match is now in the exposed or partially ejected position shown in dotted lines in Fig. 1 and burning within the lid which is held open by the match to form a protecting shield or cover. A specially shaped portion 10^a of the lid insures free circulation of air about the burning portion of the match. When it is no longer desired to make use of the present match, the plunger 12 is depressed to eject the match entirely from its groove. At the same time the lid 10 being no longer held in raised position will be closed by the action of its spring 9 imprisoning and smothering the match inside the cover. The partially burned match will be finally discarded from the container when the lid is again open during the exposing and lighting of a new match.

This device is of particular advantage in that it insures that a burnt match is thoroughly extinguished before it is thrown away and will therefore reduce the fire hazard which at present exists largely because of carelessness in throwing away burning or glowing matches. Furthermore, the device will be particularly convenient and useful inasmuch as it is possible to expose and light a match all with one hand even though both hands are gloved, for the movements in ejecting and lighting a match do not require the delicate feeling necessary to take a match from the usual match box. A further advantage from the device rests in the fact that the burning match is held within a wind-proof sheltered lid or cover and may therefore be conveniently used even in a strong wind.

While the construction shown takes the form of a pocket device, it is clear that the several features of the invention herein disclosed could equally well be applied to table fixtures or other more substantial and cumbersome devices of this nature. The invention is not limited to any particular type of mechanism but applies to any form of construction for ejecting and igniting matches from a container.

The nature and scope of the invention having been indicated and one form of the invention having been described, what is claimed is:

1. In a match receptacle the combination with a magazine for holding matches of a hinged lid for the receptacle adapted in open position to serve as a windshield, and means for causing a match to come into contact with the lid to open the lid and light the match within the shelter of the shield. 70

2. In a match receptacle the combination with a magazine for holding matches of a hinged lid for the receptacle adapted in open position to serve as a windshield, and means for ejecting a match so that the match strikes the lid to open the lid. 80

3. In a match receptacle the combination with a magazine for holding matches of means for ejecting a match and a lid adapted to open under the pressure exerted by contact of the match head therewith to form a windshield and to light the match within the shelter of the open lid. 85

4. In a match receptacle the combination with a magazine for holding matches of means for ejecting a match and a lid adapted to be opened under the pressure exerted by the match and shaped to permit the burning of the match within the shelter of the open lid. 90

5. In a match receptacle the combination with a magazine for holding matches of a yieldingly seated lid provided with a surface to ignite the match and bulged to permit the burning of the match by which it is held open and means for advancing a match into contact with the lid to open the lid and ignite the match. 100

6. In a match receptacle the combination with a magazine for holding matches of a plunger for partially ejecting matches, means for feeding matches singly to the plunger, and a lid with which the match is brought into contact to light the match and open the lid to form a windshield for the lighted match. 105

7. In a match receptacle the combination with a magazine for holding matches of a lid for the receptacle, a plunger for exposing and igniting a match against the lid, a second plunger for fully ejecting the match, and means for feeding the matches singly into the path of the plungers. 115

8. In a match receptacle the combination with a magazine for holding matches of a lid for the receptacle, a plunger for exposing and igniting a match against the lid, a second plunger for fully ejecting the match to permit the lid to close and extinguish the match, and means for feeding the matches singly into the path of the plungers. 120

9. In a match receptacle the combination with a magazine for holding matches of a plunger arranged to be manually actuated for ejecting a match, means tending to force 130

the plunger upwards into position to be manually actuated, and means normally holding the plunger in depressed position.

10. In a match receptacle the combination with a magazine for holding matches of a plunger for partially ejecting a match, a spring tending to move the plunger upwards, a second plunger for fully ejecting the match adapted to move upwardly with the first plunger, and a spring catch for normally holding the plungers in depressed position.

11. In a match receptacle the combination with a magazine for holding matches of means for exposing and automatically lighting a match therefrom, and means for retaining the burnt match within the receptacle until another match is exposed.

12. In a match receptacle the combination with a magazine for holding matches of a lid for the receptacle, a plunger for exposing and igniting a match against the lid, a second plunger for fully ejecting the match, and means for closing the lid to extinguish the match within the receptacle.

13. In a match receptacle the combination with a magazine for holding matches of means for ejecting a match, a lid adapted to be opened by contact with the ejected match and shaped to permit the burning of the match, and means for fully ejecting the match to permit the closing of the lid to extinguish the match within the lid.

14. In a match receptacle the combination with a magazine for holding matches of a lid for the receptacle, means for exposing and lighting a match within the shelter of the lid, and means for closing the lid to retain the burnt match within the lid.

In testimony whereof we have signed our names to this specification.

40 MAX C. MILLER.

FREDERICK L. JENCKES.
